UNITED STATES PATENT OFFICE.

CHARLES A. CHANTILIS, OF BELLEVUE, OHIO.

CIGARETTE HOLDER.

Application filed February 10, 1922. Serial No. 535,570.

To all whom it may concern:

Be it known that I, CHARLES A. CHANTILIS, a former subject of the King of Greece (who has declared his intention of 5 becoming a citizen of the United States and taken out his first papers), residing at Bellevue, in the county of Huron and State of Ohio, have invented certain new and useful Improvements in Cigarette Holders, 10 of which the following is a specification.

The present invention relates in general to tobacco smokers, appliances, and more particularly to a smoke-filtering device which is adapted to be associated with 15 the mouth-piece of a cigarette holder, cigar holder, pipe or the like, for the purpose of removing the nicotine and other objectionable products from the smoke before it enters the mouth of the smoker.

20 Among the objects of the invention is to provide a device of this character which embodies novel features of construction whereby it can be readily mounted in the mouth-piece or stem of a pipe or cigarette 25 holder and will operate in an effective manner to filter the smoke without interfering with the customary mounting or handling of the device.

The invention also contemplates a device 30 of this character which is inexpensive in its construction and can be manufactured in quantities and sold at a comparatively small price. A further advantage resides in the fact that the filter device is readily accessible and the filtering medium can be 35 quickly removed or replaced without difficulty whenever it becomes necessary.

With the above and other objects in view, the invention consists in certain combinations, arrangements, and associations of the 40 parts, as will more fully appear as the description proceeds, the novel features thereof being pointed out in the appended claims.

45 For a full understanding of the invention reference is to be had to the following description and accompanying drawings, in which:—

Figure 1 is a longitudinal sectional view 50 through a cigar or cigarette holder which is provided with a smoke filter embodying the features of the present invention.

Figure 2 is a top plan view thereof.

55 Figure 3 is a view similar to Figure 1 in which the invention is illustrated as applied to a tobacco pipe.

Figure 4 is a transverse sectional view on the line 4—4 of Fig. 1.

Corresponding and like parts are referred to in the following description and indicated in all of the views of the drawing by like reference characters.

Referring to Figures 1 and 2 of the drawing, which show the invention as used in connection with a cigar or cigarette holder, 60 the numeral 1 designates the mouth-piece, and 2 the tubular stem which is detachably connected to the mouth-piece and has a flared opening 3 within which the cigar or cigarette is adapted to be fitted in the usual 65 manner. The mouth-piece is provided with the usual central passage 4 through which the smoke is conveyed from the interior of the tubular stem 2 into the mouth of the smoker. A nipple 5 70 is formed at the end of the mouth-piece 1 and the rear end of the tubular stem 2 telescopes over the nipple and detachably engages the same to provide a connection 75 between the mouth-piece and the stem. 80 This rear end of the stem which engages the nipple is shown as reinforced by an exterior ferrule or band 6. This is the usual and well known construction and no 85 claim to novelty is based thereon.

Fitted upon the end of the nipple 5 is a filter cap 7 which preferably has comparatively thin walls and may be formed of any suitable material, although I contemplate making these caps of glass, since 90 glass is an inexpensive material that can be readily cleaned and it will not absorb the nicotine and other products which may be condensed from the smoke. The extremity of the nipple 5 may be rabbeted as indicated at 5^a to engage the open end of the filter cap, the other end of the filter cap being closed, and the side walls of the filter cap being provided with suitable openings, 95 such as those indicated at 8 and 9. These 100 openings are arranged so that they may be closed by the interior walls of the tubular stem and the openings 8 are arranged near the closed end of the filter cap while the openings 9 are arranged near the opposite 105 end of the filter cap. Some suitable filtering material such as the absorbent cotton 11 is placed within the cap, and the interior 110 of the tubular stem 2 is shown as provided with channels or depressions 11 which are adapted to communicate with either set of the openings 8 and 9, said openings being

85

95

100

110

so arranged that by rotating the stem 2 upon the mouth-piece the channels can be brought over the either set of openings, the other set of openings being closed.

5 These channels 11 extend forwardly beyond the filter cap 7 so that the smoke can enter the forward ends of the channels and be conveyed thereby to either set of the openings, depending upon the adjustment of 60 the parts. If the channels are in communication with the outer openings 8 the smoke will be drawn through substantially the full length of the filtering medium 10, although if the channels are in communication with 65 the openings 9 the smoke will enter the filter cap 7 at the base thereof and there will be a comparatively slight filtering action. This latter position may be desirable under some conditions, as for instance when there is 70 slight difficulty in drawing the smoke through the mouthpiece, owing to a poorly made cigar or cigarette, or a poorly packed pipe. It will be obvious, however, that the device can be very quickly adjusted and set 75 so that the smoke will enter the filter cap 7 through either the outer set of openings 8 or the inner set of openings 9. On Figure 2 I have shown the band 6 of the stem as provided with an arrow 12 which can be 80 brought into registry with either one of a pair of graduations 13 on the mouth-piece, thereby enabling the stem to be rotated and set accurately in either position, as may be desired, the channels 11 being in communication with the openings 8 when the arrow 85 12 is turned to one of the graduations 13, and being in communication with the other set of openings 9 when the arrow is turned to the other graduation 13.

40 In Figure 3 of the drawings I have illustrated the invention as applied to a conventional tobacco pipe. The bowl 14 of the pipe is provided with a stem 2^b which has the opening through the rear end thereof 90 45 enlarged or flared as indicated at 3^b, so that it can engage the nipple of a mouth-piece 1^b which is substantially identical in construction with the mouth-piece of the cigar and cigarette holder which has just been 95 described. The filter cap 7^b is identical in construction with the filter cap 7 and is arranged and mounted in substantially the same manner. In both forms of the invention the mouth-piece and stem can be readily separated at any time in the usual manner, and the filter cap 7 is then exposed so that it can be removed and the filtering medium within the same very quickly replaced. The absorbent cotton which is used as the filtering medium is so inexpensive 100 that it can be replaced as often as desired and the expense is so slight as to be negligible. As the smoke is drawn through the absorbent cotton the nicotine and quite a number of other objectionable products are condensed and absorbed so that the smoker is enabled to enjoy a cool and refreshing smoke. In order to adjust the parts to draw the smoke through the openings 8 or the openings 9, the filter cap 7 105 70 may be rotated and adjusted upon the nipple 5 instead of rotating the stem upon the mouth-piece, and this would be preferable where the invention is embodied in a tobacco pipe as indicated by Figure 3.

Having thus described my invention, what I claim as new and desire to secure by Letters Patent is:

1. In a device of the character described, the combination with a mouth piece, a filter member associated with the mouth piece, and means for causing the smoke to pass through predetermined varying lengths of the filter member to vary the filtering action upon the smoke. 110

2. In a device of the character described, the combination with a mouth piece, a filter member carried by the mouth piece, a tubular stem housing the filter member and mounted upon the mouth piece, and means 115 controlled by a relative rotation of the filter member and tubular stem for causing the smoke to pass through predetermined variable lengths of the filter member to vary the filtering action upon the smoke. 120

3. In a device of the character described, the combination of a mouth piece, a filter cap mounted thereon and provided with lateral openings, a filtering medium within the filter cap, and a tubular stem carried by the mouth piece and having interior walls adapted to close the lateral openings of the filter cap, said tubular stem being provided with an interior channel adapted to be brought into and out of registry with the lateral openings of the cap by a relative rotation of the tubular stem and cap. 125

In testimony whereof I affix my signature.

CHARLES A. CHANTILIS.
